US0D1038373S

(12) **United States Design Patent** (10) **Patent No.:** **US D1,038,373 S**
(45) **Date of Patent:** **** Aug. 6, 2024**

(54) **DRYLINE TUBE**

(71) Applicant: **Fisher & Paykel Healthcare Limited**,
Auckland (NZ)

(72) Inventors: **David-Reyner Cailun How**, Auckland (NZ); **Karla Maree Dey**, Auckland (NZ); **Manuel Dindas**, Auckland (NZ); **Paul Joseph Moody**, Auckland (NZ); **Telge Nishan Chaturanga Peiris**, Auckland (NZ)

(73) Assignee: **Fisher & Paykel Healthcare Limited**,
Auckland (NZ)

(**) Term: **15 Years**

(21) Appl. No.: **29/859,685**

(22) Filed: **Nov. 11, 2022**

Related U.S. Application Data

(62) Division of application No. 29/668,273, filed on Oct. 29, 2018, now Pat. No. Des. 973,862.

(57) **CLAIM**

The ornamental design for a dryline tube, as shown and described.

DESCRIPTION

FIG. 1 is a front, top, and right-side perspective view of a dryline tube embodying our new design.

FIG. 2 is a front view thereof.

FIG. 3 is a top view thereof.

(Continued)

FIG. 4 is a rear view thereof.

FIG. 5 is a bottom view thereof.

FIG. 6 is an enlarged left-side view thereof; and,

FIG. 7 is an enlarged right-side view thereof.

Broken lines are used to illustrate portions of the dryline tube that form no part of the claimed design.

1 Claim, 3 Drawing Sheets
